Primary Examiner — Stacia A Cadmus*(74) Attorney, Agent, or Firm* — Gable Gotwals(57) **CLAIM**

The ornamental design for a vehicle wheel, as shown and described.

DESCRIPTION

FIG. 1 is a perspective view of a vehicle wheel showing my new design.

FIG. 2 is a front elevation view.

FIG. 3 is a rear elevation view; and,

FIG. 4 is side elevation view, the top, bottom, left, and right sides being a mirror image of one another.

The broken lines shown in the drawings are included for the purpose of illustrating environmental subject matter only and form no part of the claimed design.
